United States Patent Office

Des. 203,004

Patented Nov. 23, 1965

203,004

EYEGLASS CASE

Hilda Williamson, Cherry St., R.R. 2, Stouffville,
Ontario, Canada

Filed Feb. 19, 1962, Ser. No. 68,880

Term of patent 7 years

(Cl. D57—1)

Fig. 1

Fig. 2

FIGURE 1 is a perspective view of an eyeglass case, showing my new design.

FIGURE 2 is a fragmentary rear perspective view of the edge portion.

This side not shown is substantially like the side shown.

I claim:

The ornamental design for an eyeglass case, as shown and described.
